CLAIM

The ornamental design for a terminal of video conference, as shown and described.

DESCRIPTION

FIG. 1 is a top, front and left side perspective view of a terminal of video conference showing our new design;

FIG. 2 is a bottom, rear and right side perspective view thereof;

FIG. 3 is a top, rear and left side perspective view thereof;

FIG. 4 is a bottom, front and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof; and,

FIG. 11 is an enlarged view of portion 11 in FIG. 1.

The broken lines in the drawings illustrate portions of the terminal of video conference which form no part of the claimed design.

1 Claim, 11 Drawing Sheets
